OIL CIRCUIT BREAKERS

Haakon Forwald, Ludvika, Sweden, assignor to Allmanna Svenska Elektriska Aktiebolaget, Västerås, Sweden, a corporation of Sweden

Filed May 15, 1958, Ser. No. 735,554

Claims priority, application Sweden May 21, 1957

2 Claims. (Cl. 200—150)

Oil circuit breakers are known in which a stationary contact is arranged in a confined extinguishing chamber and a movable contact pin is arranged to traverse an opening in the wall of the extinguishing chamber. In such chambers the gas pressure is increased with increasing interrupted current. As the gas pressure at opening of the breaking gap acts on the movable contact in the same direction as the force exerted from the operating mechanism of the circuit breaker, the speed of the contact will increase with increasing current. Attempts have been made to avoid this disadvantage by providing a cylindrical space in the movable contact, which space at one end is closed by a stationary piston and at the other end is in communication with the extinguishing chamber by a central channel. As the pressure in the extinguishing chamber is transmitted through the said central channel to the cylindrical space of the movable contact, a force is attained that actuates the movable contact in the direction towards the stationary contact. If the inner diameter of the cylindrical space is chosen equal to the area of the contact pin at the opening of the extinguishing chamber, a practically complete equalization of the forces generated by the pressure in the extinguishing chamber and actuating the pin is attained. The speed of the contacts may then be made independent of the interrupted current. The flow of oil into the extinguishing chamber is, however, combined with an increase of the gas volume and thus of the pressure in the extinguishing chamber, which lowers the breaking ability and may cause the chamber to burst.

The present invention concerns an oil circuit breaker with a stationary contact, arranged in an extinguishing chamber, and a movable contact traversing an opening in the wall of the extinguishing chamber and being provided with a cylindrical space, which is closed in one end by a stationary piston. The circuit breaker is chiefly characterised in that the part of the movable contact projecting into the extinguishing chamber is provided with at least one channel which allows the developed gases to escape from the extinguishing chamber, and at least one channel by which the inner space of the extinguishing chamber is in communication with the closed cylindrical space of the movable contact. The movable contact may suitably be provided with a central channel for the escape of the breaking gases, which channel is surrounded by a plurality of channels forming a communication between the extinguishing chamber and the above mentioned space in the movable contact.

By the invention a circuit breaker with extremely good breaking features is attained, which has been reached by a design allowing the speed of the movable contact with an outlet opening for the breaking gases to be inde-

2

pendent of the pressure in the extinguishing chamber and thus also independent of the interrupted current.

On the accompanying drawing a form of the invention is shown. Fig. 1 shows an extinguishing chamber arranged in an oil container and a contact projecting into said extinguishing chamber. Fig. 2 is a section of the movable contact along the line A—A. The section through the movable contact in Fig. 1 is taken along the line B—B, as shown in Fig. 2. In the figures 1 designates a container partly filled with oil. At the bottom 2 of the container an extinguishing chamber 3 of insulating material is attached. In the lower part of the extinguishing chamber 3 the stationary contact of the breaking gap is arranged. This contains a yieldably attached contact block 4, which is actuated by the spring 5 in the direction towards a locking ring 6. The extinguishing chamber 3 is in its upper part provided with an opening 7, through which the movable contact 8 of the circuit breaker traverses. The movable contact is in its upper part provided with a cylindrical space 9, which in its upper part is closed by a stationary piston 10 and which is in communication with the space 12 in the extinguishing chamber 3 through channels 11. The movable contact is in its lower part also provided with a central channel 13, by which the space 12 communicates with the space 14 outside of the extinguishing chamber. Breaking gases developed in the extinguishing chamber can escape through this channel. The movable contact 8 is by means of two rods 16 pivoted on the taps 15 joined with an operating mechanism not shown on the figure. 17 is an arc formed between the contacts of the circuit breaker.

I claim as my invention:

1. An oil circuit breaker comprising an oil container, an extinguishing chamber located inside said container and having an opening through which it communicates with the container, a first stationary contact located inside said chamber, a second contact movable in said container in the direction of its own longitudinal axis, one end of said second contact being arranged to close said opening and to project into the chamber, a said second contact having space in the other end other of, a stationary piston closing one end of said space, the space being decreased during opening movement of the second contact, the cross-section of the piston being substantially equal to the cross-sectional area of said opening whereby the forces generated by the pressure in said chamber and actuating the second contact are substantially equalized and the speed of the contacts is independent of the current, and the second contact having at least one separate equalizing channel connecting said chamber with said space and at least one separate escape channel to connect said chamber with said container when the second contact extends into the chamber.
2. An oil circuit breaker according to claim 1, in which the said escape channel is centrally located in the second contact and is surrounded by a number of equalizing channels providing communication between said chamber and said space.
